UNITED STATES PATENT OFFICE

2,553,063

HYDRAULIC PUMP

Thomas Simpson, Pattingham, near Wolverhampton, Thomas Edwards, Bilsbrook, near Wolverhampton, and Leonard Sidney Greenland, Compton, Wolverhampton, England, assignors to H. M. Hobson Limited, London, England, a company of Great Britain

Application March 25, 1949, Serial No. 33,348
In Great Britain January 19, 1949

6 Claims. (Cl. 103—38)

1

This invention relates to hydraulic pumps of the kind comprising at least one pair of pumping units of the barrel and plunger type having their outlets connected to a common delivery line and a cam mechanism, common to the two units, for imparting movement to the plungers, the cam mechanism being such that the units are effective to produce a constant rate of flow of liquid in the common delivery line.

One form of hydraulic pump of the above kind is described in our U. S. application Serial No. 789,494, which matured into Patent No. 2,548,501 on April 10, 1951, and, as explained in that application, the cam mechanism is so designed that while one plunger of each coupled pair is executing a suction stroke, the other is executing a delivery stroke to discharge liquid into the common delivery line at constant speed, while, when the discharge from the one unit is increasing immediately following its suction stroke, that of the other is correspondingly decreasing, and when the discharge from one unit is decreasing, immediately prior to the suction stroke, that of the other unit is correspondingly increasing.

One object of this invention is to provide a convenient form of regulating mechanism for varying the delivery of the pump. A further object is to provide a regulating mechanism such that, in the zero delivery condition, the pump barrels will contain the minimum quantity of liquid.

In the pump according to the invention the pump barrels are disposed radially in relation to the cam shaft and the regulating mechanism comprises a sleeve surrounding the cam mechanism, a plurality of rocker arms, for imparting movement to the plungers, each rocker arm being pivoted to the sleeve on an axis parallel to the axis of the cam shaft and carrying a follower which projects through an aperture in the sleeve and coacts with the cam mechanism, and means for rotating the sleeve in relation to the cam shaft.

As the sleeve is turned, the distance between the pivot of each rocker arm and the zone of contact between that rocker arm and its associated plunger or plungers will be varied, and therefore the stroke of the plungers will be changed. When the sleeve is turned into a position such that the pivots of the rocker arms are opposite the centre lines of the plungers no delivery takes place and it is preferred to arrange that, in this condition, the plungers are at the outer ends of their barrels (i. e. in the positions they occupy at the end of the delivery stroke).

2

so that the barrels are empty of liquid. As the sleeve is turned from this position, the stroke imparted to the plungers by the cam mechanism, and therefore the delivery of the pump, will be progressively increased. There is therefore no danger of disturbance arising from cavitation, due to trapped air, in the liquid at the minimum delivery condition, when such cavitation would be particularly harmful in the case of a fuel pump.

Preferably the sleeve is coupled to the vane of a vane-type servo motor to which liquid is supplied for the purpose of rotating the sleeve in relation to the cam shaft.

15 One form of pump according to the invention, which is intended as a fuel pump for injecting fuel into the combustion chamber of a gas turbine, will now be described in detail, by way of example, with reference to the accompanying drawings, in which—

Fig. 1 is a diagram showing the pump, the mechanism for supplying fuel to the pump and thence to the turbine, and the mechanism for adjusting the delivery of the pump,

20 Fig. 2 is a section on the line II—II in Fig. 1.
Fig. 3 is a side elevation of the pump.
Fig. 4 is a longitudinal section through the centre line of the pump,

Fig. 5 is a section on the line V—V in Fig. 3,
30 showing the pump set for maximum delivery,

Fig. 6 is a section, similar to that of Fig. 5, through part of the pump, but showing it set for zero delivery,

Fig. 7 is a section on the line VII—VII in Fig. 3,
35 Fig. 8 is a section on the line VIII—VIII in Fig. 4, and

Fig. 9 is a section on the line IX—IX in Fig. 5.
Like reference numerals designate like parts throughout the figures.

40 The hydraulic pump is shown at 10 in Fig. 1 and comprises, as later explained, 16 radially disposed pumping units of the barrel and plunger type, which are coupled in pairs to eight delivery lines 11, by which fuel is pumped to eight injection nozzles 12 in the gas turbine. These delivery lines are shown purely diagrammatically in Fig. 1, and are attached to the eight delivery outlets 13 shown in Fig. 7. As later described, 45 the pump is so designed that each coupled pair of pumping units maintains, for each setting of the pump, a constant rate of flow in the associated delivery line 11. The rate of flow in each delivery line may, however, as described later be adjusted from zero to a given maximum by

rotation of a servo vane 14 (Fig. 1) in its housing 15.

Fuel is supplied, from a reservoir 16, to the pump 10 by a gear wheel pump 17 driven by the turbine which feeds the fuel along a pipe 18 to the pump 10 at some convenient pressure, e. g. 15 lbs./sq. in. The pipe 18 communicates with an inlet 19 shown in Figs. 3, 4 and 9. The pump 17 is fitted with the usual relief valve 20 (Fig. 1), to allow excess fuel to be returned to the reservoir 16.

The position of the servo vane 14 in its housing 15 is controlled by a regulating valve 21 (Fig. 1) which is movable axially in a sleeve 22, rotatably mounted in a housing 23, by means of a regulating lever 24, pivoted at 25 and having a cam face 124 abutting against the stem of the valve 21. The sleeve 22 carries a coupling dog 26, which is held by a spring 41 in engagement with a slot 27 in the boss 28 of the servo vane 14, the dog 26 being shown uncoupled from the slot 27 in Fig. 1 for purposes of clarity. The spring 41 also holds the valve stem in engagement with the cam face 124.

A pipe 29 conducts fuel under pressure from the pipe 18 to an annular port 30 in the housing 23, and a similar annular port 31 in the housing 23 communicates with an exhaust pipe 32 leading to the reservoir 16.

Pipes 33, 34, communicating respectively with annular ports 35, 36 in the housing 23 of the same form as the ports 30, 31, lead to points in the housing 15 on opposite sides of the servo vane 14. The ports 35, 36 are shown most clearly in Fig. 2.

Radial ports 37, 38, 39 and 40 in the sleeve 22 communicate respectively with the ports 30, 31, 35 and 36 in the housing 23.

The stem of valve 21 carries a pair of end discs 42, 43 which fit closely within the sleeve 22 and are pierced by holes 44, 45 respectively. Between the end discs 42, 43 extend two helical lands 46, 47, the outer surfaces of which are in contact with the inner surface of the sleeve 22, and which divide the space between the end discs 42, 43 into two chambers 48, 49. Chamber 48 is in constant communication with the pressure pipe 29 through hole 44 and ports 37, 30, and chamber 49 is in constant communication with the exhaust pipe 32 through hole 45 and ports 38, 31. The lands 46, 47 normally seal the ports 39, 40 respectively.

Assuming now that the lever 24 is moved anti-clockwise about its pivot 25, so pushing the valve 21 to the left as seen in Fig. 1, the land 46 will unmask the port 39, connecting it to the pressure chamber 48, and the land 47 will unmask the port 40 and connect it to the exhaust chamber 49. Fuel under pressure will consequently flow through the ports 39, 35 and the pipe 33 to the housing 15 causing the servo vane 14 to rotate anticlockwise, expelling fuel to the exhaust chamber 49 through the pipe 34 and ports 36, 40. As the servo vane 14 rotates, it will cause the sleeve 22 to rotate with it until the ports 39, 40 catch up with the lands 46, 47 and are again masked by those lands. The sleeve 22 thus acts as a follow-up mechanism, and the movement of the servo vane 14 will cease when it has assumed a position corresponding to and determined by the position of the lever 24.

If the lever 24 is moved clockwise about its pivot 25, the valve 21 will be moved to the right by the spring 41. The port 39, when unmasks by the land 46, will now be connected to the exhaust chamber 49 and the port 40, when unmasks by

its land 47, will be connected to the pressure chamber 48. Consequently fuel will flow to the housing 15 through the pipe 34, and the servo vane 14 will rotate clockwise, expelling fuel to exhaust through the pipe 33. As before, the sleeve 22, turning with the servo vane 14, will catch up with the lands 46, 47 and reseat the ports 39, 40, so terminating the movement of the servo vane 14 when it has reached the position corresponding to that determined by the lever 24.

The servo vane and its housing are shown in more detail in Fig. 7. The housing 15 has inlets 50, 51, which are connected respectively to the pipes 33, 34 and the vane is duplicated, comprising two vanes 14, 14' mounted on a common hub 23 rotatable between arcuate members 52, 53 in the housing on a central sleeve 57 (Fig. 4). The space to the right of the vane 14 communicates with the space to the left of the vane 14' via a hole 54 in the boss 28, an annular space 55 within the boss and another hole 56 in the boss. The space to the left of the vane 14 communicates with the space to the right of the vane 14' in similar fashion via holes, not shown, in the boss 28, corresponding with holes 54, 56 and an annular space 58 shown in Fig. 4.

The pump 10 comprises a main cylindrical body 59 (Fig. 9), to one end of which is fitted the housing 15 of the vane servo motor. Mounted centrally in the main body is a cam shaft 60 carrying two cams 61, 62 and mounted in bearings 63, 64. The cam shaft is splined to a drive shaft 65 (see also Fig. 1) by which it is driven from the turbine.

Within the main body 59 (see in particular Figs. 4 and 5) are disposed sixteen pumping units of the barrel and plunger type, these being divided into four groups, each comprising four pump barrels 66 arranged in line. The barrels extend radially in relation to the cam shaft 60, and the groups are spaced 90° apart as clearly shown in Fig. 5. Surrounding the cams 61, 62 is a regulating sleeve 67, best seen in Fig. 9, having at one end dogs which project through circumferential slots in an end wall 70 of the housing 15, and engage cooperating dogs on the hub 28 of the servo vane. In Fig. 8 a pair of dogs 69 fixed to the hub 28 are shown projecting through a circumferential slot 68 in the end wall 70 and engaging a dog 71 on the sleeve 67. Another pair of dogs on the hub 28, not shown in Fig. 8, but diametrically opposite the dogs 69 project through another slot similar to the slot 68 and engage another dog on the sleeve 67 similar to the dog 71. When therefore the servo vane 14 rotates as already described, in response to movement of the regulating lever 24 (Fig. 1) the sleeve 67 will rotate with it.

Midway in its length the sleeve 67 has four bosses 72 (Fig. 9), within which are mounted pivot pins 76 (Fig. 5), spaced 90° apart and extending parallel to the axis of the sleeve. On each pivot pin 76 is mounted a pair of rocker arms 77 (see also Fig. 9), one on each side of the boss 72. These rocker arms 77 extend more or less circumferentially in relation to the sleeve. Each rocker arm 77 carries at its outer end a roller 78 mounted on roller bearings (not shown). The rollers 78 coact with the cams 61, 62, four with each cam (see Fig. 5), and are held in contact with the cams by tension springs 79 extending between adjacent rocker arms. As shown in Fig. 5 four tension springs 79 are associated with each group of four rollers 78. The outer

faces of the rocker arms 77 abut against the inner ends of the pump plungers 80 which are loaded by compression springs 81 which press them inwardly into contact with the rocker arms 77. Each rocker arm 77 coacts with two adjoining plungers 80 of one of the above-mentioned groups as shown in Fig. 4.

As the cams 61, 62 rotate, the rocker arms 77 are rocked to force the plungers 80 outwards to execute delivery strokes, whereafter their springs 81 return them to execute suction strokes.

The fuel inlet 19 is at the housing end of the main body and communicates, via a pair of openings 82 (Fig. 7 and Fig. 9), with eight axial fuel inlet passages 83 in the main body, two of the inlet passages being associated with each group of barrels, as shown in Fig. 5. One inlet passage 83 for each group communicates (see Fig. 9), by a duct 84 normally closed by an inlet valve 85 (see Fig. 5), with the outer end of the first and third barrels 66 reading from the left hand side of Fig. 9. The other inlet passage communicates in similar fashion with the second and fourth barrels of the group. Each inlet valve 85 opens, against the action of a spring 86, when the associated plunger 80 is executing a suction stroke.

Thus, considering the uppermost group of four pumping units, the inlets of the units marked A and B in Fig. 4 communicate, as shown in Fig. 9, with the right hand one of the two upper inlet passages 83 shown in Fig. 5, while the inlets of the other two top pumping units, marked C and D in Fig. 4, communicate with the left hand one of the two inlet passages 83 shown in Fig. 5.

In the case of the bottom group of four pumping units, the inlet connections are reversed, as will be clear from Fig. 4, the right hand bottom inlet passage 83 as seen in Fig. 5 communicating with the bottom pumping units C and D and the left hand bottom inlet passage 82 communicating with the bottom pumping units A and B.

Also associated with each group of four pumping units is a pair of discharge passages 87 (Fig. 5). In the case of the uppermost group of barrels, the right hand discharge passage 87 shown in Fig. 5 communicates with the barrels of the second and fourth units of the group, reading from the left in Fig. 4 and marked C and D, by means of a discharge valve 88 normally held closed by a spring 89. Each discharge valve 88 opens, against its spring 89, when the associated plunger is executing a delivery stroke to allow fuel to flow out of the pump barrel into the associated discharge passage 87. The other two barrels, i. e. the barrels of units A and B, communicate in precisely the same fashion with the left hand discharge passage 87 in Fig. 5.

The discharge connections of the bottom group of pumping units are also reversed. Thus, as will be clear from Fig. 5, units C and D discharge into the left hand bottom passage 87, while units A and B discharge into the right hand bottom passage 87. The eight discharge passages 87 lead to the eight delivery outlets 13 already mentioned to which are connected the eight delivery lines 11.

As will be apparent from Fig. 9, the inlet and discharge valves, 85, 88, are reversed in position for successive pumping units of the upper and bottom groups reading from the left in Fig. 9. Thus, for the upper group, the inlet valves 85 are located to the left, as seen in Fig. 5, of the units C and D, and to the right of units A and B.

Similarly, in the bottom group the inlet valves 85 are to the left (as seen in Fig. 5) of the units A and B and to the right of units C and D.

The sixteen pump barrels 66 are thus coupled in pairs to the eight discharge passages 83. Thus, the barrels of the upper units A and B are connected to one discharge passage 83 and those of upper units C and D to another discharge passage 83.

The barrels of upper units A and B are, however, associated with different cams, the plunger of unit A being actuated by the left hand cam 61 as seen in Fig. 4 and that of unit B the right hand cam 62. The cams 61, 62 are of the same shape, but are displaced 180° in phase. When, therefore, the plunger of unit A is executing a suction stroke, that of unit B will be executing a delivery stroke.

The shape of the cams 61, 62 is such that, when the discharge from either of the units A and B is increasing immediately following its suction stroke, that of the other unit is correspondingly decreasing, while when the discharge from one unit is decreasing, immediately prior to the suction stroke, that of the other unit is correspondingly increasing. The rate of flow of fuel in each delivery line is thus maintained constant at a value determined, as later explained, by the position of the sleeve 67 in relation to the cam shaft 66.

Precisely the same is true of the other pair of coupled upper units C and D; and also the two pairs of coupled bottom units A and B and C and D.

The arrangement of the side groups of units is precisely similar, as will be apparent from Fig. 5, the units again being grouped in pairs, one unit of each pair being actuated by a different one of the two cams 61, 62, discharging into a common delivery passage 87.

The rate at which fuel is delivered by the pump 10 depends upon the position of the regulating sleeve 67. When this sleeve occupies the position, shown in Fig. 6, in which the axes of the pivot pins 76 intersect the axes of the pump barrels 66, there will be no delivery from the barrels, the plungers 80 then being maintained at the outer ends of the barrels. This corresponds with one end position of the vane 14 in its housing 15. When the vane 14 is moved towards the other end of its housing 15, the sleeve 67 is turned to increase progressively the effective lengths of the rocker arms 77, so progressively increasing the stroke of the plungers 80 until finally it reaches the maximum delivery position shown in Fig. 5. The sleeve 67 is, of course, cut away where necessary, as clearly shown in Figs. 5 and 6, to enable the rollers 78 to coact with the cams 61, 62.

By rotation of the sleeve 67 therefore, the flow from the pump 10 can be adjusted from zero to a maximum, the pump always delivering fluid, at a definite rate, which remains constant at a value determined by the position of the sleeve 67. Moreover, when the sleeve is set for zero delivery, the pump plungers 80 are maintained in their outermost positions in which the pump barrels are substantially empty of fuel.

What we claim as our invention and desire to secure by Letters Patent is:

1. A hydraulic pump, comprising a cam shaft having thereon two cams, at least one pair of pumping units, each including a plunger mounted to reciprocate in a barrel, a common delivery line associated with each of said pairs of pump-

ing units and receiving the discharge therefrom, a regulating sleeve surrounding the cam shaft and rotatable in relation thereto, rocker arms pivoted on the sleeve for imparting reciprocating movement from the cams to the plungers, one of the plungers of each of said pairs of pumping units receiving movement from one of the cams and the other plunger of that pair receiving movement from the other cam and, the cams being of the same shape but displaced 180° in phase and shaped so that each pair of pumping units produces, for a given setting of the regulating sleeve, a constant flow of liquid in the associated common delivery line at a rate determined by the position of rotational adjustment of said sleeve in relation to said shaft, and manually operable means for rotating the regulating sleeve in relation to the cam shaft to vary the effective length of the rocker arms and therefore the delivery of the pump.

2. A hydraulic pump as claimed in claim 1, comprising a plurality of groups of four pumping units, the pumping units of each group being arranged in line in relation to the cam shaft, and the plungers of two pumping units of each group being operated by a common rocker arm from one of the cams while the plungers of the other two pumping units of each group are being operated by a common rocker arm from the other cam, a pair of inlet passages extending longitudinally of each group of pumping units, and a pair of discharge passages also extending longitudinally of each group of pumping units, the inlet and discharge passages communicating alternately with the pumping units of the group so that a pair of pumping units associated one with each cam receives liquid from each inlet passage and a pair of pumping units associated one with each cam discharges liquid into each discharge passage.

3. A hydraulic pump, comprising a shaft, at least one pair of pumping units, each pumping unit comprising a barrel disposed radially in relation to the shaft, a plunger in the barrel, and an inlet valve and a discharge valve at the outer end of the barrel a delivery outlet associated with each pair of pumping units and arranged to receive the discharge from both of said pumping units, a cam mechanism on the shaft for reciprocating the plungers in their respective barrels, a regulating sleeve surrounding the cam mechanism, rocker arms pivoted to the sleeve on axes parallel to that of the shaft for imparting movement from the cam mechanism to the plungers, and means for rotating said sleeve in relation to the shaft so as to vary the effective length of the rocker arms and therefore the delivery of the pump, said cam mechanism being so shaped that the flow of liquid in each of said delivery outlets is constant and determined in magnitude by the position of rotational adjustment of said sleeve in relation to said shaft and all of said plungers being maintained by the rocker arms in the positions corresponding to the termination of their delivery strokes when said sleeve is positioned with the pivotal axes of said rocker arms intersecting the centre lines of said plungers.

4. A hydraulic pump, comprising a cam shaft, having thereon two cams, at least one pair of pumping units, each including a plunger mounted to reciprocate in a barrel, a common delivery line associated with each of said pairs of pump-

ing units and receiving the discharge therefrom, a regulating sleeve surrounding the cam shaft and rotatable in relation thereto, rocker arms pivoted on the sleeve for imparting reciprocating movement from the cams to the plungers, one of the plungers of each of said pairs of pumping units receiving movement from one of the cams and the other plunger of that pair of receiving movement from the other cam, and the cams being of the same shape but displaced 180° in phase and shaped so that each pair of pumping units produces, for a given setting of the regulating sleeve, a constant flow of liquid in the associated common delivery line at a rate determined by the position of rotational adjustment of said sleeve in relation to said shaft, means for feeding fuel to the pump, a vane type servo motor having a vane coupled to said regulating sleeve, and manually operable means for controlling the supply of fuel from said fuel feeding means to said servo motor and thereby effecting rotation of said vane and sleeve in relation to said shaft to vary the effective length of the rocker arms and therefore the delivery of said pump.

5. A hydraulic pump as claimed in claim 3, comprising a vane type servo motor, including a housing and a vane movable in said housing and coupled to the sleeve, a valve casing, a conduit between each end of said housing and the valve casing, pressure and return connections to said valve casing, a valve in the valve casing which normally interrupts communication between said connections and said conduits, a manually operable regulating member for displacing the valve, according to its direction of movement, to effect alternative connections between said conduits and said connections and thereby to cause movement of the vane and regulating sleeve, and a follow-up gear for interrupting communication between said conduits and said connections when the vane has moved to a position corresponding to and determined by the position of the regulating member.

6. A hydraulic pump as claimed in claim 5, in which the valve is disposed within a ported sleeve, coupled to the vane and constituting the follow-up mechanism, and comprises helical lands normally masking a pair of ports in the sleeve and dividing the space therein into pressure and exhaust chambers which are respectively in communication with said pressure and return connections, said ports being in fluid communication with said conduits and the regulating member serving to displace the valve axially to effect alternative connections of the ports in the ported sleeve to said chambers.
